(57) **CLAIM**

The ornamental design for a gaming terminal, as shown and described.

DESCRIPTION

FIG. 1 is a front perspective view of a gaming terminal showing our new design;

FIG. 2 is a front view thereof;

FIG. 3 is a left side view thereof;

FIG. 4 is a right side view thereof; and,

FIG. 5 is a top view thereof.

The broken lines immediately adjacent to the shaded regions define the bounds of the claimed design and form no part thereof. The broken line showing of the remainder of the gaming terminal illustrates environmental structure and forms no part of the claimed design.
